DESCRIPTION

(51) **LOC (8) CL.** **10-04**
(52) **U.S. CL.** **D10/93; 92/94**
(58) **Field of Classification Search** D10/92-94; 116/DIG. 32; 177/236-245, 25.13-25.18; 340/870.02, 870.03, 870.11-870.15; 364/464.02, 364/567

FIG. 1 is a perspective view of a first embodiment human weighing scale with wall mounted display radio receiver and speakers embodying our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a perspective view of a second embodiment of the human weighing scale with wall mounted display radio receiver and speakers embodying our new design;

FIG. 9 is a top plan view of FIG. 8;

FIG. 10 is a bottom plan view of FIG. 8;

FIG. 11 is a front elevational view of FIG. 8;

FIG. 12 is a rear elevational view of FIG. 8;

FIG. 13 is a right side elevational view of FIG. 8;

FIG. 14 is a left side elevational view of FIG. 8;

FIG. 15 is a perspective view of the wall mounted display radio receiver and speakers according to the first and second embodiment of our design;

FIG. 16 is a top plan view of FIG. 15;

FIG. 17 is a bottom plan view of FIG. 15;

See application file for complete search history.
